HINGE CONSTRUCTION

Norbert L. Obrecht, Pontiac, Mich., assignor to
American Forging & Socket Company, Pontiac,
Mich., a corporation of Michigan

Application June 8, 1936, Serial No. 84,113

6 Claims. (Cl. 16—143)

This invention relates to hinge construction, and is particularly directed to improvement of hinges for doors, hatches and other closures arranged to be yieldably moved in one direction, either by gravity or spring or equivalent means, and manually operable in the reverse direction. A particular object of the invention is the provision of improved hinging means of the character indicated, having no parts which interfere with sealing of the hinged edge, whereby gasketing or the like may be arranged to provide virtually hermetic sealing of the closure.

Another important object is the provision of such an improved hinge having its relatively movable part slidably interfitted and so arranged that the closure is swingable about an axis outside of the hinge.

Another object is to incorporate in such a hinge improved holding means for the closure, automatically operable both to catch and retain the same in desired position and to release it, which holding means is controllable by movement of the door or closure itself, incorporates no special moving parts, and requires no two-handed manipulation.

Other objects and advantages will be apparent from the following description, wherein reference is made to the accompanying drawings illustrating a preferred embodiment of my invention and wherein similar reference numerals designate similar parts through the several views.

In the drawings:

Figure 1 is a perspective view of the rear portion of an automobile carrying a trunk provided with a door equipped with hinges of my improved construction.

Figure 2 is an enlarged side view of the hinge installed, corresponding to a fragmentary vertical section of the portions of the trunk near the hinged edge, parts of the hinge being also broken away and illustrated in section.

Figure 3 is a bottom view of the hinge.

Figure 4 is a view similar to Figure 2, showing a hinge of somewhat modified construction.

Figure 5 is a bottom view similar to Figure 3 of the modified hinge.

Figures 6 and 7 are views similar to Figure 2 showing further modifications.

Figure 8 is a top view of the hinge shown in Figure 7, and

Figure 9 is a cross section thereof taken substantially on the line 9—9 of Figure 7 and looking in the direction of the arrows.

Referring now to the drawings, reference char-

acter 10 designates the body of a trunk, shown as carried upon the rear of an automobile 12 and serving to illustrate a typical application of the present invention. The door 14 of the trunk is hinged at the top and indicated as forming the greater part of the back wall and top thereof. Sealing means against dust and weather is of course necessary, and where the door is of such relatively large size, it becomes something of a problem, inasmuch as although it must be tight and continuous, it cannot stick, or due to its extent the total adhesion would make the door most difficult to open. For this purpose a channel 17 encircles the door opening and at its inner edge carries an upstanding wall portion 16 adapted to engage a soft rubber gasket 15 carried by the door in position to properly meet it. The gasket may be formed with a slot to receive the rim or edge portion 16, increasing the area in sealing engagement. Channel 17 is adapted to act as a gutter for rain water, which it conducts to the bottom, where it may run from the trunk. The gasket or sealing strip 15 is continuous, and my improved hinge is so formed as to arch it and the described sealing portions at the edge. A leaf 25 secured to the door, as by the welded flanges 21, supports it by means of an arcuately formed stem portion 20 which is curved concentrically about the desired axis of swing and slidably interfitted with the similarly arched stationary support 30 or leaf portion 22. These parts may be of channeled sheet metal construction, the stem portion fitted into and supported by the fixed leaf.

The telescoping sections are guided and held against separation by a holding plate 30, rigidly secured to the inside of support 22 and spaced therefrom in such manner that the stem 20 may slide between the plate and support. Element 20 is longitudinally slotted as at 24, to allow it to travel over the spacer rivets 26, 27 by which plate 30 is secured in place, and the rivets will be seen to prevent longitudinal separation of the leaves, in cooperation with the plate which holds them against separation in parallel planes. The end of the holding plate farthest from the swingable leaf is provided with a down-bent catch portion 31, the lower surface of which, during normal swinging movement forms a part of the bearing for the stem. The remainder of the holding plate, between catch shoulder 31 and the rivet 27 which holds the other end of the plate, inclines downwardly in such manner as to allow a slight amount of rocking movement of the stem and the door about an independent horizontal axis in the

neighborhood of rivet 27, when the stem 20 is pulled out as far as rivet 26 will permit. At such time the unslotted extremity of the stem, designated 37, lies between shoulder 31 and rivet 26, and is by the weight of the raised door, which then extends outward and upwardly from the hinges, urged against the top of plate 30, to catch behind the shoulder 31 and prevent closing movement of the door. From this position it can only be freed by lifting upon the door to rock the stem in the opposite direction, allowing the latch portion 37 to descend and again pass beneath the shoulder portion 31 in closing movement of the door. Thus although the latch provided is a secure one, the door being held by the abutment of the end portion 20 with the rigid shoulder 31 carried by the holding plate 30, no special moving parts are required to effect the latching or release of the door when in raised position.

20 In Figures 4 and 5 a modified construction is shown in which the support 22a is a single vertical plate carrying a slotted guide 23 bridging a portion of its end and through which the slideable door stem 20a, also of flat construction, travels. The passage in the supporting element 22a will be seen to be narrow enough in its left-hand end, as viewed in Figure 4, to hold the stem against rocking movement while guiding it in its sliding travel, while to the right of the catch 25 shoulder 31a integrally formed in its upper surface it is sufficiently wide to allow independent vertical movement of the stem, and permit its nose or latch portion 37a to rise and catch beneath the shoulder 31a. At such time the stem 30 will be seen to rock about the one outermost corner of the guide, designated 27a, while when it is desired to release the catch, it is merely necessary to lift the door sufficiently to allow the latch portion 37a to drop clear of the shoulder 35 31a, after which the door may be closed in similar fashion. A pin 38b carried by the end of the stem limits its outward movement, and guide 23 is slotted to provide clearance therefor. The pin may also, by abutment with the securing flange 40 of the support, limit inward movement of the stem.

The construction shown in Figure 6, although generally similar to that shown in Figures 1 and 2, incorporates a support 22b hung directly beneath the bracket portion 21b by which it is secured to the body, and incorporates positive latching means comprising a spring catch element 30b carried by and urged into the guide passage in portion 23b by its own resiliency, and 45 so adapted to engage beneath the end of the stem 20b when the latter is pulled out to the limit of its travel by full opening of the door, as to prevent reclosure thereof until the spring catch piece has been retracted, which may be effected 50 manually by means of a small cam 40 rockable by a finger piece as 41 to force back the catch. The cam and finger piece may be journaled in the support. Obviously, when, as is usual, the hinged element is supported upon two such 55 hinges, the latching element need be incorporated in but one.

Figure 7 shows a somewhat modified construction also somewhat resembling and functioning similarly to the embodiment first disclosed, but 60 having its supporting track portion 32c carried from below by a bracket portion 21c, while the channelled slideable stem element 20c fitted thereto may be retained by the over-engaging holding plate 30c, the function of which, and the 65 operation of the entire construction, will be seen

to be similar. Equivalent portions which need no detailed redescription have accordingly been given like reference characters distinguished by the addition of the letter "a" to each.

What I claim is:

1. Hinging means comprising a pair of slidably interconnected elements arced about a common center outside both, means for securing the outer end of each element to a support or hinged element, said elements having guiding portions holding the same against cocking with relation to their common center when fully slid inward with relation to each other, but allowing relative hinging movement with relation to such center, and differently proportioned portions allowing such cocking movement of one with relation to the other when partly pulled out, and detent means for holding said elements against undesired sliding movement when so partly pulled out, including a shouldered portion carried by one 20 and engageable and disengageable by a portion carried by the other by such cocking movement of one element with relation to the other.

2. In a hinge construction, a pair of slidably interconnected elements at least one thereof arced about a center outside itself, means for securing the outer end of each element to a support or hinged object, combined guiding and latching means carried by one element including a guiding portion near but spaced from its free end for holding the other element against relative cocking movement about an eccentric center, said guiding portion having a stepped section providing a shoulder extending laterally from said element by which the guiding portion is carried, said shoulder lying nearer the free end of the latter and allowing relative cocking movement of the other element when sufficiently pulled out with respect thereto, so that a part of such pulled out element lies in such stepped section and adjacent the shoulder, and another shoulder at the opposite end of said stepped section and for preventing inward return movement of said elements while cocked with respect to their normal path of sliding movement.

3. In a hinge construction, slidably interconnected elements at least one whereof is arced about a center outside itself, means for securing the outer end of each element to a support or hinged object, means preventing separation of said elements and limiting their sliding travel with respect to each other, one of said elements having a stepped shoulder-forming portion near but spaced from its free end and normally out of engagement with the other element but engageable therewith by cocking movement of one element relatively to the other about an eccentric center when they are sufficiently pulled out with respect to each other, to prevent their inward sliding movement while so cocked.

4. Hinging means comprising a pair of slidably interconnected elements arced substantially about a common center located outside both, means for securing the opposite outer ends of said elements one to a support and the other to a hinged member, whereby said elements may slide with relation to one another as said hinged member is swung with relation to the support, the means interconnecting said elements including a laterally enlarged portion which allows limited eccentric 70 rocking movement of one with relation to the other, and detent means comprising laterally interengageable abutment portions carried by said elements engageable and disengageable by such eccentric rocking movement to selectively prevent 75

and permit said sliding movement of one element relatively to the other.

5. A hinge construction comprising a pair of slidably interfitting elements at least one whereof is arched about an axis outside itself, said elements being movable about such axis with respect to each other, means for securing the outer end of each element to a support or hinged object, means for limiting relative sliding movement of 10 said elements, and detent means for releasably holding said elements against relative movement, including portions engageable by rocking movement of one element with respect to the other about an axis eccentric to the first mentioned 15 axis.

6. Hinging means comprising similarly arched and slidably interconnected elements, means for

fastening the outer end of each of said elements to a hinged member or support, said elements having guiding portions to prevent relative rocking movement thereof during the greater part of their sliding movement, and locking means for preventing inward sliding movement of said members with relation to each other when partly pulled out, comprising an abutment portion carried by one of said elements and a laterally enlarged portion carried by the other providing 10 a cooperating abutment and allowing limited eccentric rocking movement of said elements when said abutment portions are aligned, whereby said abutment portions may be engaged and disengaged by such eccentric rocking movement. 15

NORBERT L. OBRECHT.
